CLAIM

The ornamental design for slat for slat-belt treadmill, as shown and described.

DESCRIPTION

FIG. 1 is a perspective view of the design for slat for slat-belt treadmill according to the present disclosure;

FIG. 2 is another perspective view of the design for slat for slat-belt treadmill according to the present disclosure;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top plan view thereof; and,

FIG. 9 is an enlarged cross-sectional view taken in the direction of line A-A of FIG. 7.

The broken lines shown in the drawings illustrate portions of the slat for slat-belt treadmill that form no part of the claimed design.
